(57) **CLAIM**

The ornamental design for a lighting assembly, as shown and described.

DESCRIPTION

FIG. 1 is a front perspective view of a lighting assembly showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front isometric view of the lighting assembly of FIGS. 1-7 without surface shading and without disclaimed subject matter;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken line showing in FIGS. 1-7 of the lighting assembly is for environmental purposes only and forms no part of the claimed design.
